Application filed October 14, 1893. Serial No. 488,182. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification.

The design consists of an arrangement of ornamental scrolls forming panels with a vase-like ornament filled with flowers and leaves in the center of each panel and festoons of flowers and leaves hanging from the scrolls and connecting the panels as represented in the accompanying drawing. Below said panels and forming the base of said panels are scrolls diverging to the right and left with branches of flowers and leaves springing therefrom as shown in the drawing. The border

or upper portion of the design is also formed of the same ornamental scrolls forming panels with vase-like ornaments filled with flowers and leaves in the center of said panels, and a festoon of flowers and leaves connecting the scrolls below said panels as shown in the drawing. 25

What I claim is—

1. The design for wall paper herein shown and described.
2. In the design for wall paper, the border herein shown and described. 30
